UNITED STATES PATENT OFFICE.

CLARA V. HAVENS, OF NEW YORK, N. Y.

WASHABLE DOLL.

Application filed September 1, 1921. Serial No. 497,555.

To all whom it may concern:

Be it known that I, CLARA V. HAVENS, a citizen of the United States, residing in the city, county, and State of New York, have 5 invented a new and useful Washable Doll, of which the following is a specification.

My invention consists of a doll formed of fabric that may be made up or assembled into the form, the head and body of a doll, 10 and taken apart or knocked down, when it may be readily washed, after which it may be again made up in clean condition, the means employed and the construction and manipulation of the various members being 15 hereinafter set forth.

The invention is satisfactorily illustrated in the accompanying drawing, but the important instrumentalities thereof may be varied, and so it is to be understood that the 20 invention is not limited to the specific details shown and described, as long as they are within the spirit or scope of the claims.

Figure 1 represents a front elevation of a washable doll embodying my invention.

Figure 2 represents a side elevation thereof.

Figure 3 represents a rear elevation thereof.

Figure 4 represents a blank from which 30 the head and body of the doll is convertible.

Figures 5, 6 and 7 represent plan views illustrating the various steps of converting the blank into a doll.

Figure 8 represents a vertical section of a 35 portion on line 8—8 Figure 4.

Similar numerals of reference indicate corresponding parts in the figures.

Referring to the drawings:—
1 designates the head of the doll, 2 the 40 body and 3 the skirt thereof, said members being formed of a piece 4 of toweling or other suitable washable material, which piece is shown in normal condition in Figure 4, said piece consisting of the flat quadrilateral part 5 and the depending folded part 6, the latter being narrower than the former, and stitched thereto on the line 14.

In the part 5 is the right-lined fold line 7, which extends transversely across the same, 50 the diagonal fold lines 8, which latter extend from the center of the fold line 7 to the sides of said part 5 and the fold lines 9, which extend at a different angle from the fold lines 8 towards the end of said part 5, 55 which subsequently will become the bottom of said part.

The several fold lines enumerated are preferably formed by stitches in the part 5, so that they are permanent on the part. On the part 5, which becomes the front of the 60 doll is the face 10 of the doll, which is formed of a piece 11 of fabric, which is stitched to the part 5 and left open at the lower end, so that cotton or other batting 12 may be inserted behind said piece 11 and so 65 puff-out the latter, see Figure 8.

On said piece is embroidered, painted or printed the simulation of a mouth, nose, eyes and hair, so that the piece presents the 70 appearance of the face of the doll.

To the lower end of the piece 11 are secured the strings or tapes 13, which are adapted to be passed around the neck 14 of the doll to close said end and to retain the head 1 in position, as will be hereinafter 75 further referred to.

In making up the doll, the part 5 is folded down on the line 7 when the lower portion of said part 5 is folded downwardly on itself to the stitch line of said part 6 for shortening said part 5 and placing a portion of the part 6 back of said folded part 5, and another portion of the latter depending from the part 5 at the stitch line 14^x and extending partly below the bottom of the part 5, 85 all as shown in Figure 5, while the face 10 of the doll and the strings 13 appear on the front of the part 5.

The parts as thus set up are reversed, as 90 shown in Figure 6, when portions of the sides of the part 5 are folded on the diagonal lines 8 upon the backs of the contiguous portions of the parts 5 and 6, producing the triangular laps 15 of double thicknesses of the fabric, the result being shown in said 95 Figure 6. Then said triangular laps are again folded on themselves on the diagonal lines 9, and upon the upper portions of the part 6, producing the triangular laps 16, the result being shown in Figure 7.

The tops of the laps and of the part 5 now form as in Figure 7 the peak 18, which primarily is above the head of the face, the same being turned down on the top line 17 of the head on the adjacent portions of the laps 9, and comprising part of the back of the head 9 of the doll thus imparting some rotundity to the back of the head, and thus divesting said back of flatness, see Figures 2 and 3. Then the strings 13 are run around 105 the neck of the doll and engaged with the lower end of the turned down peak, 110

holds said peak in position, preventing it from opening out and forming the neck 14, which is well defined, while at the same time, the several laps are prevented from 5 opening out.

It will be seen that the laps form the body of the doll, while the exterior of said body simulates a cape or wrap, while the skirt 10 3 is that of the skirt of a dress, and so the clothing of the doll is made up, while the head 10 is imposed on the part of the material of which the clothing is composed, a doll of novel nature thus being produced.

It is evident that when the strings or tapes 15 are untied, the peak 18 may be raised, and the laps 15 and 16 unfolded and the piece 4 and 6 of the fabric opened out, as in Figure 4. The piece 1 may be washed and the doll thus cleaned, after which said piece may 20 be manipulated to reconvert it into the doll as in Figures 1, 2 and 3, as hereinbefore explained.

Having thus described my invention, what I claim as new and desire to secure by Letters Patent, is:—

1. A doll formed of a piece of washable fabric folded and lapped to form the face and body of the doll and the simulation of a cape thereon.

2. A doll of the character stated, formed of a piece of fabric folded and formed into a head, laps on said piece folded and formed into a body, and a member pendant from said body folded and formed into a skirt.

3. A doll of the character stated, formed of a piece of fabric folded and formed into a head, a body and a skirt, said head having thereon a face, a neck intermediate of said body and head, and means for closing said

40 neck and consequently said body.

4. A doll of the character stated formed of a piece of fabric having thereon fold lines adapting the piece to be folded thereon and converted into a head, laps to be folded

45 thereon and converted into a body, and an intermediate neck.

5. A doll of the character stated formed of a piece of fabric having thereon diagonal and transverse fold lines adapting the piece

to be converted into a head, a body, a neck 50 intermediate of said body and head, a skirt pendant from the body, and means for retaining said body in a closed condition, said head having thereon the simulation of a 55 face.

6. In a doll of the character stated, a piece of fabric adapted to be formed into a head, a piece of material with a simulation thereon of a face, the latter-named piece being imposed on the said head, a puffing between 60 said pieces, and a piece of material folded around and secured to the head.

7. In a doll of the character stated, a piece of fabric adapted to be formed into a head, and having laps adapted to be formed 65 into a body, a neck intermediate of said body and head, a peak beyond the head and foldable upon the back of the head, and means for closing said neck and consequently said body adapted to prevent the opening of said body and neck.

8. In a doll of the character stated, a piece of fabric adapted to be formed into a head, a face on said head, a peak on said 75 piece adapted to be folded down on the back of said head and below the neck to fill out said back, and means for retaining said peak in position.

9. In a doll of the character stated, a piece of fabric adapted to be folded upon diagonal and transverse lines and formed into a head, a body, a neck and a skirt, said head having thereon a face, means for closing said neck and a body and a peak on said piece adapted to form a continuity of the head 80 and to be folded on the back of the latter to fill out the same, and means to retain said head, neck and body in closed position.

10. A piece of fabric for forming a doll, the same embodying a rectangular part with 90 depending folded portion of less width, the rectangular part having a transverse fold line, and diagonal fold lines to form triangular laps.

CLARA V. HAVENS.
